UNITED STATES PATENT OFFICE.

AUGUST C. TAPPE, OF CINCINNATI, OHIO, ASSIGNOR OF ONE-HALF TO
ROBERT T. BADGLEY, OF NEW YORK, N. Y.

HORSESHOE-PAD.

No. 836,150.

Specification of Letters Patent.

Patented Nov. 20, 1906.

Application filed June 6, 1906. Serial No. 320,481.

To all whom it may concern:

Be it known that I, AUGUST C. TAPPE, a citizen of the United States, residing at Cincinnati, in the county of Hamilton, State of Ohio, have invented a certain new and useful Improvement in Hoof-Pads, of which the following is a specification.

More specifically my invention relates to an improvement in that class of hoof-pads which 10 were described and claimed by me as my invention in Letters Patent of the United States No. 690,482, dated January 7, 1902. By the modification of the pad designed in that patent, which modification is described 15 in full hereinafter, I succeed in obtaining a pad having an air-cushion the suction-power of which is much greater than that in my former pad and which offers a greater resistance to slipping. The new pad is also designed to 20 permit of free ingress and egress of air to and from the horse's hoof in such a way as to prevent the detachment of the rubber from the leather, which is so objectionable in some of the forms of horseshoe-pads heretofore used. 25 The improvement also makes less likely a puncture of the rubber tube in which air is incased.

In the accompanying drawings, which serve to illustrate my invention, Figure 1 is a 30 side elevation in section, showing the pad with its backing of leather and iron shoe nailed to the hoof of the horse. Fig. 2 is a rear sectional elevation of the same. Fig. 3 is a plan view of the rubber pad itself, showing the stitching which secures the rubber to the leather below it. Fig. 4 is a plan view of 35 the leather, showing attachment to the rubber and also the partitions of the under side of the rubber pad. Fig. 5 shows the top of 40 the pad before the leather is attached to it.

Referring to the drawings, A is the rubber pad, consisting of a flanged part b, thickened heel portion c, raised hollow bead d, and central cavity e. On the top side of the pad 45 forming the inner side of the bead is a cavity f, separated by rubber partitions g.

B is the leather attached to the top of rubber pad by means of stitching, cement, or otherwise.

C is the iron shoe.

h h are apertures in the leather leading to the cavity f.

The important feature of this pad is that the air tube or channel d is strengthened and supported by the partitions g, and the provision of an air-outlet for each of the partitions serves to prevent the rubber from becoming detached from the leather at any point of the pad, for they relieve the compression of air in those compartments. It 55 will be noticed, moreover, that the bead d is elliptical in shape and is adapted to secure a better bearing for the horse's hoof. By this construction I also avoid the difficulties caused in my former construction by the central opening in the rubber and the air-passages leading to the channels. 60

Having thus described my invention, what I claim is—

1. A horseshoe-pad, having a thickened heel portion, a thin flange so constructed as to receive a horseshoe, a raised hollow bead, and partitions dividing said hollow bead.

2. A horseshoe-pad, having a thickened heel portion, a thin flange so constructed as 75 to receive a horseshoe, a raised hollow bead, partitions dividing said hollow bead, and a leather backing for the top of said pad.

3. A horseshoe-pad, having thickened heel portion, a thin flange so constructed as 80 to receive a horseshoe, a raised hollow bead, partitions dividing said hollow bead, a leather backing for said pad, said leather having air-apertures over each chamber, into which said hollow bead is divided. 85

In witness whereof I have hereunto set my hand this 11th day of May, 1906.

AUGUST C. TAPPE.

In presence of—

CLARENCE G. GALSTON,
H. E. BROPHY.
